H. DE CORREVONT

FITTING FOR BATHTUBS AND THE LIKE

Filed March 3, 1923

Inventor.
Howard de Correvont
By Fred Gelach
his Atty.

UNITED STATES PATENT OFFICE.

HOWARD DE CORREVONT, OF CHICAGO, ILLINOIS.

FITTING FOR BATHTUBS AND THE LIKE.

Application filed March 3, 1923. Serial No. 622,473.

To all whom it may concern:

Be it known that I, HOWARD DE CORREVONT, a citizen of the United States, and a resident of Chicago, in the county of Cook and State 5 of Illinois, have invented certain new and useful Improvements in Fittings for Bathtubs and the like, of which the following is a full, clear, and exact description.

The invention relates to discharge fittings 10 for bath tubs and the like and its object is to provide an improved fitting for use in connection with a bottom drain and an overflow from the tub. Another object is to provide an improved fitting which is adapt- 15 ed to be rendered accessible for inspection or repair without the necessity of providing a removable panel, as usual in connection with bath tubs. Other objects of the invention will appear from the following specifica- 20 tion.

The invention consists in the several novel features hereinafter set forth and more particularly defined by claims at the conclusion hereof.

25 In the drawings: Fig. 1 is a side elevation of a fitting embodying the invention. Fig. 2 is a similar view of a portion of the fitting showing the parts in position to render the drain valve accessible for removal.

30 The invention is exemplified as applied to a bath tub to which is connected the usual bottom drain 4 and an overflow 5 which may be of any suitable construction and as well understood in the art. The bottom drain 4 is connected to a fitting 6 by means of a packed joint 7 and said fitting is connected by a packed joint 8 to the drain-pipe 9. The overflow 5 is connected to a T-fitting 10 by a packed joint 11 and a vertical pipe 12 is connected to the lower end of fitting 10 to conduct the overflow downwardly to the fitting 6. A pipe 13 is connected to the upper end of fitting 10 and a rod 14 extends through pipes 12 and 13 and has its upper end connected to any suitable shifting device or handle, as well understood in the art. Rod 14 is suitably connected to operate a sleeve valve 15 which is adapted to close on a seat 16 and to control the flow of liquid 45 from bottom-drain 4 to the fitting 6. When the valve 15 is lifted, drainage can flow from drain 4 to the discharge pipe 9. The lower end of rod 14 is screw-threaded to a stem 17, to the lower end of which is secured a valve 18 which is adapted to close against a seat 20 formed in the lower end of valve 15.

Valve 18 is adapted to close the lower end of valve 15 so that when the latter is raised to permit the discharge of drainage from the bottom of the tub, communication between the fitting 6 and the overflow 5 will be closed to prevent the waste (dirty water) from surging up into and through overflow pipe 12. A stop plate 22 is suitably secured on the upper end of stem 17 and a nut 23 threaded to the rod 14 is adapted to engage plate 22 to limit the drop of valve 18. Plate 22 has openings therein to permit water to pass from pipe 12 into sleeve valve 15. When rod 14 is lowered, as shown in Fig. 70 1, sleeve-valve 15 will be closed to hold the water in the tub and, at such time, valve 18 will be open to permit the overflow to pass through valve 15 into pipe 9. When rod 14 is raised, sleeve valve 15 will be positioned 75 so that water from drain 4 will be free to pass into pipe 9 and valve 18 will be closed to prevent any drainage from surging or passing up into pipe 12.

In practice, it is occasionally necessary 80 to clean out, repair or grind the valves 18, 20, and, in order to make it possible to readily remove the valves for these purposes, a pipe section 24 has its lower end connected by a screw-thread 25 to the upper end of fitting 6. The upper end of pipe-section 24 laps the lower end of pipe 12 and is connected thereto by a coupling 27 which is provided with a packing 28 to provide a tight joint between section 24 and pipe 12. 90 Packing 28 is provided between section 24 and the upper end of fitting 6. When it is desired to have access to the valves, it is only necessary to unscrew coupling 27 and slide section 24 upwardly on pipe 12, as 95 shown in Fig. 2. When the rod 14 is raised, the sleeve valve 15 and valve 18 can be lifted into and removed through the gap between pipe 12 and fitting 6 upon its disconnection from rod 14. The pipe 12 and its connec- 100 tions are usually installed in a wall around the bath tub so that they are inaccessible and, heretofore, so far as I am aware, it has been customary to install a removable panel in the wall so that it would not be necessary 105 to tear down the wall when a repair was necessary to the drain fittings. An inherent advantage of the invention is that these removable panels may be dispensed with. In building the wall around the fittings, it is 110 customary to provide a base-board 30 around the lower portion of the wall and along the

floor. The plaster of the wall 31 is omitted, as at 32, behind the base-board 30 so that upon removal of the base-board, the pipe sections, bottom 4 and its connections will be 5 accessible. As a result, it is only necessary to remove the base-board to provide the desired access to the fittings.

The invention is not to be understood as restricted to the details set forth, since these 10 may be modified within the scope of the appended claims, without departing from the spirit and scope of the invention.

Having thus described the invention, what I claim as new and desire to secure by Letters Patent, is:

1. In a drain installation, the combination of a drain pipe, a drain valve, an operating connection extending upwardly from the valve, and an overflow pipe connected 20 to the drain pipe comprising a fixed upper pipe section around the operating connection and a lower pipe section adjacent the valve and slideable upwardly on the fixed section, the lower section when raised providing an opening through which the valve may be removed laterally without removing the fixed section or the drain pipe.

2. In a drain installation, the combination of a drain pipe, an overflow pipe connected 30 to the drain pipe and comprising a fixed upper pipe section and a lower pipe section slideable upwardly on the fixed section, a sleeve valve slideable from the fitting into the lower pipe section, and an operating connection extending upwardly from the valve and through said overflow pipe, said lower section when raised providing an opening through which the sleeve valve may be removed laterally without removing the 40 fixed section or the drain pipe.

3. In a drain installation, the combination of a fitting having an outlet, a drain connection from the bottom of a receptacle to the fitting, a valve adapted to close the 45 bottom drain connection, an overflow pipe separately connected to the upper portion of the receptacle, and means operable with the valve for preventing flow from the bottom drain connection through the overflow pipe when the valve is in its open position, and to permit flow from the overflow pipe

to said outlet when the valve is in its closed position.

4. In a drain installation, the combination of a fitting having an outlet, a drain connection from the bottom of a receptacle to the fitting, a sleeve valve adapted to close the bottom drain connection, an overflow pipe separately connected to the upper portion of the receptacle, and means operable 55 with the sleeve valve for preventing flow from the bottom drain connection through the overflow pipe when the valve is in its open position and to permit flow from the overflow pipe to said outlet when the valve is in its closed position.

5. In a drain connection, the combination of a fitting having an outlet, a drain connection from the bottom of a receptacle to the fitting, a sleeve valve adapted to close 70 the drain connection, an overflow pipe separately connected to the upper portion of the receptacle, an operating connection extending upwardly from the valve and through said overflow pipe, and means operable 75 with the valve for preventing flow from the bottom drain connection through the overflow pipe when the valve is in its open position and to permit flow from the overflow pipe to said outlet when the valve is in its closed position.

6. In apparatus of the character described, the combination of a fitting, a drain-pipe leading from the fitting, a bottom drain leading into the fitting, an overflow pipe 85 connected to said fitting, a sleeve valve in said fitting and for closing the bottom drain, and a valve slidably mounted in said sleeve-valve for controlling the overflow.

7. In apparatus of the character described, the combination of a fitting, a drain-pipe leading from the fitting, a bottom drain leading into the fitting, an overflow pipe comprising a removable pipe section 95 connected to said fitting, a sleeve valve removable upon removal of said section, for closing the bottom drain connection, and a valve removable with said sleeve valve, for controlling the discharge of the overflow.

Signed at Chicago, Illinois, this 28th day 100 of February, 1923.

HOWARD DE CORREVONT.
